CLAIM

The ornamental design for a liquid crystal television, as shown and described.

DESCRIPTION

FIG. 1 is a front perspective view from above of a liquid crystal television, showing my new design;

FIG. 2 is a front view thereof;

FIG. 3 is a right side view thereof;

FIG. 4 is a rear view thereof;

FIG. 5 is a top plan view thereof;

FIG. 6 is a bottom plan view thereof;

FIG. 7 is another front view thereof, showing a liquid crystal television with a base being attached to the front of a main body;

FIG. 8 is another right side view thereof, showing a liquid crystal television with a base being attached to the front of a main body;

FIG. 9 is another front view thereof, showing a liquid crystal television with a base detached;

FIG. 10 is another right side view thereof, showing a liquid crystal television with a base detached;

FIG. 11 is a front view of a base; and,

FIG. 12 is a rear view of a base.

The elements of FIGS. 9-12 are shown separately for ease of illustration only.
